UNITED STATES PATENT OFFICE.

GEORGE HEIDMAN, OF CHICAGO, ILLINOIS.

BRAKE-GEAR MOUNTING.

Application filed November 15, 1926. Serial No. 148,365.

My invention relates to mountings of the gear mechanism for operating the hand brakes of railway cars; that is to say the invention relates more particularly to means 5 for mounting the gear mechanism on the end sill of a railroad car underframe.

The objects and advantages of my invention will be readily apparent from the detailed description of the accompanying drawings wherein—

Figure 1 is a top plan view of my improved mounting secured to the underframe end sill of which only a portion is shown.

Figure 2 illustrates the same in elevation.

Figure 3 is a partial sectional view and side elevation, with a portion of end sill in section.

Figure 4 is a perspective view of a supporting plate or bracket.

Figure 5 is a partial sectional and side elevation showing a modified form attached to an end sill of which only a portion is shown in section.

Figure 6 is a perspective view of the modified form of bracket supporting member shown in Figure 5.

In the exemplification of the invention as disclosed in Figures 1 to 4, inclusive, the brake gear mounting is shown secured to the end sill 10 of a car underframe and consists of a top plate member 11 having a flat upper surface at the inner end which is adapted to extend flush with the bottom flange of the end sill member 10 and to terminate at the inner edge of the lower flange of the end sill as shown in Figure 3.

The outer end of the top plate may be slightly offset as shown and is provided with depending sides 12, 12. The upper surface 40 of the top plate is provided with a transversely disposed flange or upstanding wall 13 reenforced by webs or ribs 14; the flange 13 being adapted to extend flush with the outer face of the end sill and to be riveted thereto. The top plate at the outer end is also suitably apertured to receive the brake staff, a portion whereof is shown at 15, and to provide suitable bearings for the drive element or gear 16 which also has bearing 50 in a boss formation 17 on a lower plate 18, see Figure 2.

The outer end of plate 18 is provided with upstanding sides 19, 19 preferably adapted to overlap the sides 12, 12 on the inner sides 55 thereof and to be riveted or otherwise secured thereto at 20; the upstanding sides 19

being of a height so that they may abut against the bottom of the top plate and thus provide a suitable spaced relation between the plates to receive the drive element or gear 60 16. The bottom plate 18 has an integrally disposed leg or portion 21 reenforced by means of lip 22; the leg being preferably disposed into a lower horizontal plane to provide sufficient spacing for the driven element 65 or gear 23 and the chain spool or drum 24 while at the same time maintaining the driven gear in a proper plane relative to the drive gear 16. The inner end of the leg 21 is apertured to receive a pin 25 which is preferably provided with a sleeve or spacing member 26 on which the driven elements, composed of driven gear 23 and spool 24, rotate.

The upper end of the pin 25 is supported 75 by means of a bracket member or plate 27 which therefore also supports the driven elements in place. The bracket member 27 is of an angular or stepped formation more clearly shown in Figures 3 and 4 consisting 80 of the lower horizontally disposed portion 28, apertured at 29 to receive the upper end of the journal bolt or pin 25, and the adjacent upwardly disposed portion 30, against which the inner end of the top plate 11 abuts; 85 said portion also abutting against the inner edge of the lower flange of the end sill 10. The upstanding vertically disposed portion 30 connects with the upper horizontally disposed portion 31 which is adapted to lap or 90 extend flush with the top face of the lower flange of the end sill 10 and to be riveted thereto as shown at 32. These rivets, if desired, may also extend through the inner end of the top plate 11. The upper horizontal surface 31 terminates in the upwardly disposed portion or wall 33 which is adapted to extend flush with the inner side of the web of the end sill 10. The vertically disposed wall or portion 33 is preferably 100 made to extend beyond the sides of the main portion of the bracket plate and these extended ends, like the intermediate or main portion, are apertured at 34 to receive the rivets 35 whereby the bracket is secured to 105 the end sill member 10. The rivets 35 are shown also employed for riveting the upstanding flange 13 of the top plate to the end sill. The bracket plate 27 is shown provided with the side walls or flanges 36, 36 110 for reenforcing the plate.

In order to permit proper rotation of the

driven elements 23, 24, washers 37, 37 may be employed. It is apparent from the construction shown that the housing is securely held in place on the end sill and that the inward 5 pulls or strains will be transmitted through the bracket plate 27 to the end sill; the stepped face of the bracket plate providing an abutting ledge for the top plate 11 of the housing.

10 It is apparent from the construction shown that removal of the drive and driven elements for repair or replacement may be readily accomplished without necessitating removal of the top and bottom plates of the housing 15 or of the bracket plate 27, as the journal pin 25 can be readily removed by unscrewing both nuts 25^a, therefrom (if a headed bolt is not used). The possibility of thus removing and renewing the gearing and chain spool or drum 20 obviates the necessity of removing all rivets between housing members and the car end sill, with the result that a great saving in time, labor and expense is accomplished through the use of my structure; while at the same 25 time a rigid thrust receiving bracket plate or member is provided adapted to withstand inward pulling strains.

In Figures 5 and 6 I illustrate a modified form of the invention wherein the top plate 38 is substantially similar to top plate 11 and 30 provided with the upstanding flange 39 which is adapted to extend flush with the forward face of the end sill 10, with the inner end of the top plate 38 riveted at 40 to the 35 lower inwardly disposed flange of the end sill and terminating with said flange. The mounting disclosed in Figure 5 also involves a bottom plate 18 which is identical with that shown in Figures 1 to 3; the top and bottom 40 plates being provided with side walls at the outer ends which are riveted together as previously described; the two plates providing a suitable housing for the drive and driven 45 elements which may be of any well known construction and actuated by means of a brake staff, a portion of which is shown at 15.

In this construction, the driven elements 23, 24 are journaled on the pin portion 41 of a bracket member 42; the pin portion 41, 50 adjacent to the juncture between the vertically disposed lower end and the upper sloping end, being preferably provided with an integral shoulder 43, while the lower end is reduced and threaded at 44 to extend through a 55 suitable opening in the bottom plate 18 and to receive a suitable nut as at 45. The upper sloping end of the pin portion is shown formed integral with the laterally disposed plate portion 46 which is intended to lie flush 60 with the web portion of the end sill 10 and to be riveted thereto as shown at 47 in Figure 5; these rivets preferably being the same rivets for securing the upstanding flange 39 to the opposite side of the end sill. The vertically disposed pin portion 41 is preferably

shown provided with a sleeve 48 on which the driven gear 23 and spool or drum 24 rotate, said sleeve also constituting a spacer element between the shoulder 43 of the bracket member and the inwardly disposed end of the 70 lower or bottom plate 18; and this pin portion may also be provided with a washer as shown at 49 in Figure 5 adapted to take up any wear induced by the rotating elements. With this construction, it is apparent that 75 the gear mechanism can be removed and replaced when found necessary by merely removing the rivets 47 without necessitating the removal of any other rivets; the major portion of the housing or mounting therefore 80 remaining intact.

The upper part of the pin portion of the bracket member 42 is shown circular in cross section above the shoulder 43, but it is evident that this portion may be of any cross-sectional configuration as is also true in connection with the contour of the bracket member 27 shown in Figure 4; the constructions, however, being believed to be the simplest 85 exemplifications of the invention which has been described in terms employed merely as terms of description and not as terms of limitation, as structural modifications are possible and may be made without, however, departing from the spirit of my invention. 90

What I claim is:

1. In a brake gear mounting, the combination of a top plate adapted to be secured to an end sill, a bottom plate secured to said top plate, drive and driven elements mounted between the plates, with means for transmitting the pulling strains on the driven elements to the car end sill, said means involving a bracket portion adapted to be secured to the inner face of the end sill and depend across 100 the inner end of the top plate and a journal portion for the driven elements removably secured to the bracket portion. 105

2. In a brake gear mounting, the combination of a top plate adapted to be secured to a car end sill, a bottom plate secured at one end to said top plate, drive and driven elements mounted between said plates, with means for rotatably supporting the driven elements in place and for transmitting pulling strains to the car end sill, said means involving an end sill engaging portion adapted to extend across the inner end of the top plate and a journal providing portion for the driven elements, said journal providing portion being 110 adapted to receive the up-thrusts of the free inner end of the bottom plate. 115

3. A brake gear mounting comprising a top member, a bottom member, the two members being secured together in spaced relation, drive and driven elements rotatably mounted on the bottom member, means whereby the top member is secured to an end sill, and means for rotatably holding the driven elements in place, said means being 125 130

formed to lap the inner end of the top member and to be secured to the inner face of the end sill.

4. A brake gear mounting comprising a top member, a bottom member extending into a plane rearward of the top member, rotatable drive and driven elements mounted on the bottom member, and a bracket element arranged rearward of the inner end of the top member, with one end secured at the journal point of the driven elements while the other end is adapted to be secured to the car frame rearward of the point of connection between the top member and the car frame.
- 10 5. In a brake gear mounting, the combination of a top plate secured to a car end sill,

a bottom plate secured to the top plate, drive elements mounted between the forward ends of both plates, driven elements mounted on the rear inner end of the bottom plate, with 20 means, independent of both plates, for transmitting the pulling strains to the car end sill, said means depending below the inner end of the top plate and involving a journal portion for the driven elements, a bracket portion 25 adapted to be secured to the inner side of the end sill to extend rearward of and depend beneath the plane of the top plate, and means for transmitting the up-thrust of the driven elements through the bracket portion to the 30 car end sill.

GEORGE HEIDMAN.
